C. RIGBY

GOLF CLUB

Filed April 18, 1927

INVENTOR.

CHARLES RIGBY,
BY F. H. HULBERT.

UNITED STATES PATENT OFFICE.

CHARLES RIGBY, OF CINCINNATI, OHIO.

GOLF CLUB.

Application filed April 18, 1927. Serial No. 184,734.

My invention relates to golf clubs, and between the sections, the parts being in partly 55 connected relation.

5 whereby the golf club may be taken apart for convenience in carrying the same, and 5 whereby a single handle may be arranged to serve for a number of heads, and whereby handles of different lengths may be provided for a given shaft.

It is the object of my invention to provide 10 a golf club with a novel joint in the length of the club, to divide the club into sections which may be readily carried for instance in a suit case, and so constructed and arranged in novel manner that the sections may be 15 quickly and conveniently assembled and disconnected.

A further object of my invention is to provide a tubular shaft for a club with fixed 20 plugs and a rotatable collar provided with novel means to associate and dissociate the sections of the club.

25 My present invention is an improvement on the inventions shown, described and claimed in Letters Patent for improvement in golf clubs, issued to me January 4, 1927, as No. 1,613,360, and in my copending application for patent on improvements in golf clubs, filed in the United States Patent Office December 6, 1926, as Serial No. 30 152,853.

In golf clubs made in sections it is important that the joints be firmly locked together in non-rotative relation. I provide positive associating and dissociating means 35 whereby the sections can be readily assembled or taken apart by a partial turn of the locking member.

The invention will be further readily understood from the following description and 40 claims, and from the drawings, in which latter:

Fig. 1 is a side elevation of my improved club of standard length.

Fig. 2 is a similar view of the same showing a short handle section.

Fig. 3 is a longitudinal section, taken on the line 3—3 of Fig. 1, partly broken away, showing my improved means for connecting the sections of the golf club.

50 Fig. 4 is a side elevation of the same, partly broken away.

Fig. 5 is a side elevation of the same, partly broken away and partly in section for exposure of the interior of the connection be-

Fig. 6 is a side view of the same, with the shell in section.

Fig. 7 is a cross-section of the same, taken in the plane of the line 7—7 of Fig. 3; and, 60

Fig. 8 is a cross-section of the same, taken in the plane of the line 8—8 of Fig. 6.

I have shown my invention applied to a club having a tubular steel shaft 21 provided with a head 22 and a handle 23. The 65 shaft is divided at 24, forming an upper handle section 25 and a lower head section 26. One of the sections, exemplified as the handle section 25, is provided with a plug 27 which is rigidly secured therein, as by 70 brazing. The plug 27 has an extension 28, which forms a tapered shank.

The other section of the shaft, shown as the head section 26, has a plug 29 fixed in its upper end, as by being brazed therein. 75 This plug has a tapered bore 30, arranged to receive the tapered shank 28.

The complementary walls of the taper shank and tapered bore may be provided with a relief portion or portions for aiding 80 in their ready assembly and release. Thus the tapered shank is provided with a tapered portion 31, at the body of the plug, and a tapered outer end 32. Intermediate of the two tapered portions, the shank is undercut, 85 as at 33.

I provide positioning means between the sections to prevent relative turning between the sections so that the blow of the head upon the ball may not turn the head and 90 may not result in torsional yield of the rod. Thus I provide a cross pin 37 positioned in the tapered shank 28. The ends of the pin 37 are received in slots 38 in the upper end of the lower shaft-section for arresting relative rotation between the shaft-sections. The slots 38 extend lengthwise of the shaft-sections.

The pins are preferably spaced slightly from the bottom of the slots 38, and the 100 proximate ends of the shaft-sections and the plugs therein are also preferably spaced slightly from each other, when the sections are assembled, so as to permit the wedging action between the tapered shank and its 105 socket to have full effect.

A sleeve 41 is received about the proximate ends of the shaft-sections and has operative

connection with each of the shaft-sections, including bayonet slot, cam and pin connections for drawing the sections toward one another. The sleeve is exemplified as held in

5 endwise relation to the lower end of the handle section by means of a pin 42 fixed to the handle section. The sleeve is provided with a slot 43 in which the pin 42 is received. This connection permits the sleeve to be 10 turned about the handle section and retains the sleeve on said section to prevent loss of the sleeve.

The sleeve is also received about the upper end of the head-section and is provided with 15 a bayonet slot 44. The head-section is provided with a pin 45 which coacts with the walls of the bayonet slot.

The bayonet slot has a mouth 46 opening in the lower edge of the sleeve. The bayonet slot comprises an entering portion 47 which is substantially parallel with the axis of the sleeve, and a laterally extending cam portion 48, merging with the inner end of the entering portion 47. The incline of the 20 walls of the cam slot at the entrance end of said slot is quite pronounced compared with the incline of the walls in the cam slot proper, so that an initial quick endwise movement between the tapered shank and the wall of its complementary bore is followed by a slower forceful endwise movement between said shank and wall of said bore to firmly wedge said shank in said bore with comparatively little turning force applied 25 to the sleeve.

A cover, shown as a shell 51, is fixed to the sleeve, as by brazing or shrinking the same thereon, and is received across the outer edges of the walls of the slots in said 40 sleeve for hiding said slots. It is also provided with knurled surfaces 52 for readily manually turning said sleeve. The shell is provided with an observation hole 53 registering with one end of the slot 43, so that 45 the pin 42 in the slot 43 may be observed when it is located at that end of said slot.

When the shaft-sections are to be assembled, the sleeve is rotated for positioning one end of the slot 43 against the pin 42, which 50 also places the pin 42 in registry with the hole 53.

When now the proximate ends of the shaft-sections are brought together, with the 55 pin 45 of the head-section in the entering portion 47 of the bayonet slot, the pin 37 is located in the slot 38, for placing the shaft sections and the sleeve in non-rotative relation for ease of assembling the shaft sections in axial direction.

60 The shaft-sections are then pushed manually toward each other so that the pin 45 is placed in registry with the entering portion of the cam slot in the sleeve. Rotation of the sleeve is effected by manually turning 65 the sleeve, by which movement the cam walls

at the entrance end and in the body of the cam slot and the pin 45 act to draw the two shaft-sections toward each other for rigidly connecting the same.

The respective walls of the slot 43 and the 70 respective walls of the cam portion 48 coact with the pins on the respective shaft-sections for causing approach between said shaft-sections when said sleeve is rotated in one direction, and causing separation between 75 said shaft-sections when said sleeve is rotated in the opposite direction, the latter separation being to sufficient extent so that, when the pin 45 reaches the low end of the cam slot, the shaft-sections may be readily 80 pulled apart manually for separating the same.

My improved construction provides ready and simple means for connecting and disconnecting the shaft-sections by a partial rotation of one of the connecting parts, and the assembling and taking apart of the golf 85 stick may be readily and quickly effected.

The incline of the cam faces at the entrance end of the cam slot is pronounced to 90 cause quick coacting movement between the taper faces of the taper shank and the wall of its socket, and the incline of the cam faces in the cam slot proper is slight, to cause respectively, a firm wedging and ready 95 release between said taper shank and the wall of its socket by slight turning force applied between the sleeve and the shanks.

It is of course obvious that changes may be made in the preferred form of my invention herein described without departing from the spirit of my invention embraced in the accompanying claims.

Having thus fully described my invention, what I claim as new, and desire to secure by Letters Patent, is:

1. A golf club comprising a handle-section and a head-section, one of said sections provided with a taper bore and the other of said sections provided with a tapered shank 110 forming a wedge connection between said sections, a sleeve rotatable about the proximate ends of said sections, means to hold said sleeve to one of said sections in both directions lengthwise of said sleeve during 115 rotation of said sleeve, and a bayonet slot and pin connection between said sleeve and the other of said sections.

2. A golf club comprising a handle section and a head section, one of said sections provided with a taper bore and the other of said sections provided with a tapered shank forming a wedge connection between said sections, and a sleeve rotatable about the proximate ends of said sections, one end of 120 said sleeve provided with a slot extending in a plane substantially perpendicular to the axis of said sleeve and the other end of said sleeve provided with a bayonet slot, said respective sections provided with pins in said 125 130

slots, and said sleeve provided with a cover for said slots.

3. A golf club comprising a handle section and a head section, positioning means interposed between said sections holding said sections in non-rotative relation with each other and permitting relative movement between them in axial direction, a sleeve rotatable about the proximate ends of said sections, means holding said sleeve endwise to one of said sections, and a bayonet slot and pin connection between said sleeve and the other of said sections, said bayonet slot comprising a portion substantially parallel with the axis of said shanks and a cam portion, said first-named portion coacting with its pin during coactive relations between said positioning means for non-rotative relation between both said sections and said sleeve, and said cam portion coacting with said last-named pin during rotation of said sleeve for drawing said sections toward one another during continuance of coactive relation of said positioning means.

4. A golf club comprising a handle section and a head section, one of said sections provided with a taper bore and the other of said sections provided with a tapered shank forming a wedge connection between said sections, a sleeve about the proximate ends of said sections, a slot and pin connection between said sleeve and one of said sections wherein the slot lies substantially in a plane perpendicular to the axis of said section, and a bayonet slot and pin connection between said sleeve and the other of said sections, said bayonet slot comprising a portion substantially parallel with the axis of said last-named section and a cam portion, said first-named portion and said last-named pin arranged for coactive relation during relative axial movements between said sleeve and both said sections, and said cam portion and said last-named pin arranged for coactive relation at the end of said last-named movement by rotation of said sleeve for drawing said sections toward one another.

5. A golf club comprising a handle section and a head section, a sleeve about the proximate ends of said sections, said sleeve provided with a slot for each of said sections, said respective sections provided with pins for said respective slots, said slots and pins comprising a bayonet slot and pin connection, an endwise limiting connection and a cam connection, arranged by opposite rota-

tion of said sleeve to draw said sections toward one another and to separate said sections.

6. A golf club comprising a handle section and a head section, means at the proximate ends of said sections comprising a sleeve received about the proximate ends of said sections, said sleeve having a slot therein extending in a plane substantially perpendicular to the axis of said sleeve, a pin on one of said sections coacting with said slot for holding said sleeve and said last-named section in endwise relation, said sleeve provided with a bayonet slot having a mouth in the end of said sleeve and a cam portion, a pin on the other of said sections coacting with the walls of said last-named slot, said cam portion of said slot having complementary opposite cam walls, both said cam walls complementary to said last-named pin, constructed and arranged for respectively drawing said sections toward one another and for separating said sections endwise by relative rotations in opposite directions between said sleeve and said sections, and a cover on said sleeve across the walls of said slots.

7. A golf club comprising a handle section and a head section, means between said sections for holding said sections in non-rotative relation and permitting axial movement between said sections, a sleeve received about the proximate ends of said sections, one end of said sleeve provided with a slot, the other end of said sleeve provided with a bayonet slot having a mouth at the other end of said sleeve, said slots comprising an entering portion extending from said mouth substantially parallel with the axis of said sections and a cam portion extending laterally, said sections provided with pins coacting with the walls of said respective slots, and a cover on said sleeve across said slots, said cover provided with an observation opening at one end of said first-named slot so arranged that when said pin in said first-named slot is at said observation opening and said second-named pin is in said entering portion of said bayonet slot, said first-named connections are in line with each other for telescopingly connecting said sections and said sleeve, and arranged whereby said sections are drawn in endwise direction toward each other by rotation of said sleeve.

In testimony whereof, I have hereunto signed my name.

CHARLES RIGBY.
